(57) **CLAIM**

The ornamental design for an automatic soap dispenser, as shown and described.

DESCRIPTION

FIG. 1 is a perspective view of an automatic soap dispenser, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another perspective view thereof, mounted on a base;

FIG. 9 is another perspective view thereof, mounted on another base; and,

FIG. 10 is another perspective view thereof, mounted on a stand.

The dashed broken lines illustrate portions of the automatic soap dispenser that form no part of the claimed design. The dashed broken lines showing a base in FIG. 8, another base in FIG. 9 and a stand in FIG. 10 are for the purpose of illustrating environmental structure, and form no part of the claimed design.
